(57) **CLAIM**

The ornamental design for a “television set,” as shown and described.

DESCRIPTION

FIG. 1 is a top, front and right side perspective view of a television set according to my design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a top, rear and right side perspective view without the desktop stand and in a position supported in part by a rear leg;

FIG. 9 is a front elevational view of the embodiment hereof illustrated in FIG. 8, as viewed perpendicular to the television set screen;

FIG. 10 is a rear elevational view thereof;

FIG. 11 is a top plan view thereof;

FIG. 12 is a bottom plan view thereof;

FIG. 13 is a left side elevational view thereof; and,

FIG. 14 is a right side elevational view thereof.
